UNITED STATES PATENT OFFICE.

ANTHONY GEORGE TRAEGER AND JOSEPH JOHN TRAEGER, OF TIMBER LAKE,
SOUTH DAKOTA.

COMBINED END GATE AND SCOOP BOARD FOR WAGON BOXES.

Application filed January 19, 1927. Serial No. 162,104.

This invention relates to combined end gates and scoop boards for wagon boxes and has for its primary object to provide an end gate scoop board construction particularly 5 adapted for grain wagons so that the grain may be readily discharged from the wagon or to facilitate the proper loading of the wagon.

A further object resides in the provision 10 of such a combined end gate and scoop board that is of extremely simple construction inexpensive of manufacture and installation and that comprises means whereby the board may be rigidly secured to the wagon 15 box and wherein the same may be readily released at its upper or lower end to facilitate loading or unloading of the wagon box.

The invention further aims to dispense 20 with all cleats and bars within the wagon box which is a great disadvantage in the use of end gates and scoop boards now in use for the reason that the grain will invariably catch behind or in front of said cleats or bars resulting in the inefficient 25 operation of the board to open or closed position.

Other objects will become apparent as the 30 nature of the invention is better understood, the same comprising the novel form, combination, and arrangement of parts herein- 35 after more fully described, shown in the accompanying drawings and claimed.

In the drawings wherein like reference 40 characters indicate corresponding parts throughout the several views:

Figure 1 is a perspective of a wagon box 45 equipped with the combined end gate and scoop board constructed in accordance with the present invention.

Figure 2 is a fragmentary section through 50 the rear end of the box disclosing the end gate in such a position as to provide a loading scoop board.

Figure 3 is a similar view disclosing the 55 board in closed position.

Figure 4 is a fragmentary side elevation 60 of the board end of the wagon, the board per se being disclosed in dotted lines as being swung away from the wagon box at its lower end so as to facilitate the unloading of the box.

Figure 5 is a detail perspective of one of 65 the upper corners of the board end of the box, the board being removed therefrom, and

Figure 6 is a top plan view of said corner disclosing the adjacent board locking bar in full line closed position and in dotted line open position.

Now having particular reference to the 60 drawings, 5 designates a wagon box open at its rear end and provided at said rear end and at its outer sides with vertical angle bars 6-6. The end board 7 is of generally conventional construction and is provided 65 at its opposite vertical edges with inwardly directed wings 8-8 that engage within the box 5 for providing a tight fit between the sides of the end board and the sides of the box and also for guiding the grain into the 70 box when the board is used for grain loading purposes as indicated in Figure 2.

The outer side of the end board 7 is provided adjacent its upper and lower edges with horizontal cleats 9-9 between the 75 center of which and said end board are pivotally mounted hand levers 10-10. Pivoted to these hand levers at opposite sides of their pivotal connections are oppositely extending bolt bars 11-11, 11-11, 80 the outer ends of the lower pair of which are adapted for engagement within sockets 12-12 formed in the sides of the wagon box and said angle bars 6-6.

The outer ends of the upper pair of bolt 85 rods 11-11 are adapted for engagement within horizontal slots 13-13 formed in the sides of the box and said angle bars 6-6 at the upper ends thereof. The extreme ends of said upper bolt rods are formed with 90 heads 14 that overlie the edges of the slots 13, the outer ends of which are provided with outwardly extending lugs 15-15 against which said heads will strike so as to prevent the outward movement of the end 95 board at its upper end when the heads are drawn tight against the slots as indicated by the full lines in Figure 6. However, when the complementary lever 10 is moved in a direction toward the left in Figure 1, 100 these heads 14 will be forced outwardly beyond the lugs 15-15 so that the end board may be outwardly swung at its upper end so as to provide a scoop board as in Figure 2, it being of course understood that the bolt 105 rods 11-11 at the lower end of the end board act as pivots therefor. In a like manner when the lower bolt rods 11-11 are withdrawn from the sockets 12, the lower end of the end board will swing outwardly 110

as indicated by the dotted lines in Figure 4, in which instance the upper bolt rods 11—11 afford pivots for the upper end of the end board.

For limiting the inward swinging movement of the lower end of the end board, the opposite edges thereof at said lower end are provided with cleats 16—16 that will engage the ends of the wagon box side walls as clearly indicated in Figures 1 and 3.

Secured to the side walls of the wagon box directly inwardly of the end board 7 is a pair of clamps 17—17 to which are connected chain lengths 18 that are in turn connected at their outer ends to the end board 7 for limiting the outward swinging thereof when the upper bolt bars are released.

It will thus be seen that I have provided a highly novel, simple and efficient combined end gate and scoop board that is well adapted for all the purposes heretofore designated and even though I have herein shown and described the invention as consisting of certain detail structural elements, it is nevertheless to be understood that minor changes may be made therein without effecting the spirit and scope of the appended claim.

Having thus described the invention, what I claim as new is:

In combination with a wagon box, open at its rear end, metallic bars secured to the outer faces of the sides of the box at the rear edges thereof, an end board for disposition within the open rear end of the

wagon box, wings extending laterally from the side edges of the end board for snug engagement with the inner faces of the sides of the wagon box, pairs of bolt rods on the outer side of the end board adjacent the upper and lower edges thereof, the sides of the wagon box and said bars being provided with registering openings adjacent the lower edges thereof through which the outer ends of the lower pair of bolt rods are slideable, said wagon box sides and the bars being formed with registering slots which extend inwardly from the outer edges of the sides of the bars adjacent the upper edges thereof and through which the outer ends of the upper bolt rods are slideable, said upper and lower pairs of bolt rods being selectively disengaged from the sides of the wagon box and the respective bars whereby the end board may be swung from the box either at its upper or lower edge portion, ears extending laterally from each of the bars on opposite sides of the open end of the slot, and heads formed on the outer ends of the upper end of the pair of bolt rods adapted to engage the inner sides of the ears when said bolt rods are in one position whereby to provide a pivot on which the upper edge portion of the end board may swing when the lower pair of bolt rods are disengaged from the registering openings in the lower portions of the sides and bars respectively.

In testimony whereof we affix our signatures.

ANTHONY GEORGE TRAEGER.
JOSEPH JOHN TRAEGER.
